UNITED STATES PATENT OFFICE.

LOUIS C. NICHOLS, OF MILWAUKEE, WISCONSIN, ASSIGNOR, BY MESNE ASSIGNMENTS,
TO ALLIS-CHALMERS MANUFACTURING COMPANY, A CORPORATION OF DELAWARE.

TRANSFORMER.

1,232,834.

Specification of Letters Patent. Patented July 10, 1917.

Application filed July 22, 1911. Serial No. 639,959.

To all whom it may concern:

Be it known that I, LOUIS C. NICHOLS, a citizen of the United States, residing at Milwaukee, in the county of Milwaukee and 5 State of Wisconsin, have invented certain new and useful Improvements in Transformers, of which the following is a full, clear, and exact specification.

My invention relates to transformers.

10 In fluid filled transformers there is more or less so-called breathing, that is, the insulating fluid, which in the present case is oil, expands upon becoming heated, and contracts when the heat is dissipated. During 15 this breathing action or expansion and contraction of the fluid, moisture in small quantities might be drawn into the transformer casings. Again, due to various reasons, water particles may be present in the 20 insulating fluid. The moisture or water particles present within the transformer casings are undesirable and may prove injurious if collected in sufficient quantities.

It is therefore the object of this invention 25 to maintain in a dry condition the insulating fluid in transformers.

The invention is illustrated in the accompanying drawing, which is a longitudinal sectional view of a transformer equipped 30 with my invention.

The various novel features of the invention will be apparent from the description and drawing and will be particularly set forth in the appended claims.

35 Upon a base 10 is mounted a transformer inclosed in a casing having a main body portion 11, a bottom 12, and cover 13. Inside of the casing is a frame 14 on which is supported a laminated core 16. High and 40 low voltage windings 17 and 18 respectively are subdivided into a number of thin flat coils which present a large cooling surface, and which are wound on said core. The coils are separated from each other, forming 45 spaces through which a fluid may pass to maintain the coils in a cool and economical operating condition. The frame 14 is reinforced by bolts 19 which retain the laminae of the core in a fixed position.

50 Located exterior to the main casing and retained a predetermined distance therefrom is a shell 20. This shell comprises two metal parts 21 which are also held predetermined distances apart and are reinforced 55 by brackets 22 to which the metal parts are

secured by rivets. The main casing and shell are connected at their extreme end portions by pipes 23, in this way providing a system for fluid circulation through the transformer, connecting pipes, and outside shell. 60 Due to the shell 20 being retained at a predetermined distance from the main casing, a passageway is formed between the main casing and shell to permit the flow of a cooling fluid through said passageway. 65

Also located within the transformer casing 11 is a partition or separating shield 15, preferably of insulating material, which divides the interior of the transformer casing into two compartments, an upper compartment 25 and a lower compartment 24. Mounted in the upper chamber 25, and preferably on the partition 15, is a receptacle 26 containing a drying agent adapted to absorb moisture or water particles if there 70 be any in the oil. This drying agent may comprise a series of blotters arranged in any convenient manner, or it may consist of calcium oxide, or any other material which is capable of absorbing moisture. A pipe 75 27, extending practically from the bottom of the lower compartment 24, passes through the partition 15 and extends into the receptacle 26. Another pipe 28 passes from the receptacle 26, in which the drying means 80 is located, and extends practically to the upper surface of the partition 15.

The insulating fluid in this particular case is oil, the lower compartment 24 being completely filled therewith and the upper 90 compartment 25 containing oil normally to the level indicated by the line 'o—o'. When the oil comes in contact with the operating transformer it gradually becomes heated, rises, and the cooler oil takes its place, causing a general upward flow within the inner transformer casing. During this flow, part of the oil passes out through the upper connecting pipes 23, down through the shell 20 and again enters the main transformer casing through the lower connecting pipes 23. While passing through the connecting pipes and the outer shell the oil is cooled by the 95 circulating cooling medium which passes between the main casing and the outer casing. Also, when the oil becomes heated it expands and passes from the lower compartment 24, together with water particles which might collect in the bottom of the casing 11, up through the pipe 27 and into 100 105 110

- the receptacle 26 containing the drying agent, any water particles being removed in this receptacle and the oil passing out into the upper compartment 25 of the casing.
- 5 Upon cooling, the oil contracts and part of the oil in the upper chamber 25 passes into the receptacle 26, together with any moisture which might collect therein, any moisture being absorbed in the receptacle. 26
- 10 and the oil passing through pipe 27 into the lower compartment. Therefore, during this breathing or expansion and contraction of the insulating fluid, water or moisture which has collected in the lower compartment of the transformer casing will be forced up during the expansion of the fluid, through the pipe 27 and absorbed in the drying receptacle 26, and any water or moisture collected in the upper compartment 25, 15 would, upon contraction of the insulating fluid, be forced through pipe 28 and the drying receptacle where the moisture will likewise be taken out of the insulating fluid.
- 20 It is therefore evident that no matter how moisture is collected in either of the compartments, such water is soon absorbed and the insulating fluid maintained in a dry condition. The transformer casing, or casing in which any similar electrical apparatus may be located, may be divided into any number of compartments and any number of drying receptacles may be used. The breathing action of the insulating fluid is 25 automatic and no matter what movement the insulating fluid makes upon expanding or contracting, all moisture in said fluid is readily removed.
- Other arrangements and modifications 30 may be made, and I intend to cover all such arrangements and modifications which do not depart from the spirit and scope of my invention as set forth in the appended claims.
- 45 What I claim as new is:
1. In combination, a casing having two compartments, an insulating liquid in said compartments, an electrical device immersed in one of said compartments, means located in one of said compartments for drying said insulating liquid, and means for conveying said liquid from one compartment through said drying means into the other compartment upon a change in volume 55 of said liquid.
  2. In combination, a casing having a plurality of compartments, an insulating liquid located in said compartments, a transformer in one of said compartments, means located in a second compartment for absorbing moisture from said liquid, and means for conveying said liquid from said first compartment through said absorbing means into the second compartment upon 60 expansion of said liquid, and for conveying
- said liquid from said second compartment, through said absorbing means, and back into said first compartment upon contraction of said liquid.
3. In combination, a casing having two compartments, electrical apparatus immersed in insulating fluid in one of said compartments, means within said casing for providing fluid communication between said compartments, and means effective to absorb moisture contained in said fluid, said latter means being inserted in said fluid communicating means whereby during the passage of fluid from either compartment to the other moisture contained in said fluid is absorbed therefrom. 70
- 75
4. In combination, a casing having two compartments, electrical apparatus immersed in insulating fluid in one of said compartments, and means within said casing for absorbing moisture contained in said fluid, said means communicating with the compartment containing said electrical apparatus at a point adjacent the lower end of said apparatus. 80
- 85
- 90
5. A casing adapted to contain insulating fluid and divided into a plurality of compartments, a communicating passage between said compartments and opening into one of said compartments at a point appreciably below the normal level of fluid within said latter compartment, and moisture absorbing means located in said communicating passage. 95
6. An oil containing casing for electrical apparatus, and means within said casing with which said oil is adapted to come in contact for absorbing moisture therefrom, said means comprising a fluid conveying element communicating with said casing at a point adjacent the lower end of said electrical apparatus when the latter is in operative position in said casing. 100
- 105
7. In combination, a casing containing electrical apparatus immersed in insulating fluid, and means associated with said casing and operative during expansion and contraction of the insulating fluid therein incident to the operation of said electrical apparatus for removing moisture that may collect in said casing, said means comprising a fluid conveying element communicating with the interior of said casing at a point below the normal level of insulating fluid therein, and moisture absorbing means inserted in said fluid conveying element and effective to absorb the moisture from fluid passing therethrough. 110
- 115
- 120
8. In combination, a casing containing electrical apparatus immersed in insulating fluid, and means comprising a fluid conveying element associated with said casing and forming a normal inlet and outlet for insulating fluid to and from, respectively, the apparatus containing portion of said casing, 125
- 130

- 15 said means being effective during expansion and contraction of said insulating fluid incident to the normal operation of said apparatus to remove moisture that may collect adjacent the bottom of the apparatus-containing portion of said casing and to permit the entrance of insulating fluid while preventing the entrance of moisture to said casing.
- 10 9. In combination, a casing comprising a plurality of compartments, electrical apparatus immersed in insulating fluid in one of said compartments, and means within said casing for providing fluid communication 15 between said compartments and communicating with the apparatus-containing compartment adjacent the lowest point of such apparatus, said means comprising means for absorbing moisture contained in 20 said insulating fluid as the latter passes

from one compartment to the other on expansion or contraction thereof incident to the normal operation of said apparatus.

10. In combination, a casing, electrical apparatus immersed in insulating fluid in 25 said casing, said casing having a plurality of compartments, and means within said casing for providing fluid communication between said compartments, said means comprising means for absorbing moisture 30 contained in said insulating fluid as the latter passes from one compartment to the other.

Milwaukee, Wis., July 5, 1911.

In testimony whereof I affix my signature, 35 in the presence of two witnesses.

LOUIS C. NICHOLS.
